UNITED STATES PATENT OFFICE.

WARREN B. FLANDERS, OF WILKINSBURG, PENNSYLVANIA, ASSIGNOR TO WESTINGHOUSE ELECTRIC & MANUFACTURING CO., A CORPORATION OF PENNSYLVANIA

APPARATUS FOR CONSERVING MOTIVE FLUID.

1,399,758.

Specification of Letters Patent. Patented Dec. 13, 1921.

Original application filed July 22, 1915, Serial No. 41,285. Divided and this application filed July 6, 1918. Serial No. 243,656.

To all whom it may concern:

Be it known that I, WARREN B. FLANDERS, a citizen of the United States, and a resident of Wilkinsburg, in the county of Allegheny and State of Pennsylvania, have made a new and useful Invention in Apparatus for Conserving Motive Fluid, which is a division of an application for patent filed July 22, 1915, Serial No. 41,285, of which the following is a specification.

This invention relates to the conservation of motive fluid, hereinafter called steam, and particularly to the conservation of steam in power plants in connection with the feed water heating system.

An object of this invention is to provide simple and improved means for venting air or other non-condensable gases from feed water heaters and particularly heaters which are continuously or at times during their operation subjected to pressures above atmosphere.

A further object is to provide a heater which may be employed in connection with steam conserving apparatus and in which simple and improved means are employed for discharging air and non-condensable gases without wasting steam.

A further object of the invention is to produce a new and improved feed water heating system in which means are employed for maintaining the pressure of the steam delivered to the feed water heater substantially constant and in which simple and improved means are employed for venting air or non-condensable gases delivered to the feed water heater.

A further object is to produce a system for heating feed water and for conserving the steam available for heating the feed water, in which improved means are employed for venting air and non-condensable gases introduced into the system with the steam or with the water to be heated.

These and other objects, which will be made apparent throughout the further description of my invention are attained by means of a feed water heating system herein described and illustrated in the drawing accompanying and forming a part hereof.

In the drawing I have illustrated diagrammatically a feed water heating system which forms an embodiment of my invention.

In power plants, or similar installations, it is customary to deliver the steam exhausted from the steam driven auxiliaries to a feed water heater, where it is employed in heating the water prior to its delivery to the steam generators. It will be apparent that if the exhaust steam so delivered to the heater is sufficient in quantity to heat the feed water to a determined temperature during periods of full load on the steam generators, it will be in excess during periods of light load, since the load on the generators varies in approximately direct ratio to variations in the load on the prime movers or main power developing units, whereas the amount of steam exhausted from the auxiliaries remains substantially constant regardless of variations in the load on the prime movers. On the other hand, if the number of auxiliaries, delivering exhaust steam to the feed water heater, is so proportioned that the steam delivered to the heater during normal loads on the main power units or prime movers, is just sufficient to be economically employed in heating the feed water, there will not be sufficient steam to raise the feed water to the desired temperature when the main power units are developing maximum power.

In order, therefore, to conserve the steam and to increase the economy of the entire plant or installation, means have been provided for automatically delivering the excess steam which cannot be efficiently employed in the feed water heater to a power developing mechanism or some other apparatus in which the heat of the steam can be usefully employed. Means have also been employed for automatically augmenting the supply of heating steam by delivering additional steam to the heater when the normal source of heating steam supply is insufficient to maintain the feed water at the desired temperature. With such apparatus the so-called open heater cannot be employed, since the automatic regulation of the steam supply to the heater is ordinarily accomplished through variations in the pressure of the steam supplied, and consequently the heater, although it may be of the open heater type, is subjected to pressure which at times exceeds atmospheric pressure. Under such conditions, it is difficult to effect a removal of the air and other non-condens-

able fluids from the heater without dissipating heat energy.

My invention overcomes this difficulty, and, as illustrated, includes a feed water heater which is adapted to receive steam under pressure and is provided with a vent port for venting air or other non-condensable gases from the heater. The vent port communicates with apparatus of such capacity that it is capable of efficiently or economically employing the fluid vented from the heater during the periods of greatest fluid pressure within the heater. In the apparatus illustrated, the means for utilizing the vented fluid is shown as an auxiliary heater which operates to condense the steam vented from the main heater and which also abstracts heat from the air or other non-condensable gases vented from the main heater.

The illustrated embodiment of my invention includes a prime mover or main power developing unit 3, which is illustrated diagrammatically as a steam turbine, having a low pressure stage 3^a between two rotor sections 3^b and 3^c which are operated in series by high pressure steam entering the turbine at 3^d and exhausting into a condenser 4, which may be of any type to which condensing water is delivered by means of a pump 5, through a pipe or passage 6, the pump receiving water from a pipe 6^a. I have illustrated diagrammatically a steam turbine 7 for driving the pump 5. This turbine receives steam through a pipe or passage 8 and the steam exhaust therefrom is delivered through a pipe or passage 9 to a receiver or exhaust main 10, with which the exhaust of other steam driven auxiliaries may communicate. I have also shown another auxiliary turbine 7^a arranged to discharge into the exhaust main 10 by means of a pipe 9^a.

A feed water heater 11 is diagrammatically illustrated in the drawing and as shown receives heating fluid from the receiver 10 through a passage 13 which is provided with a valve 13^a. The horizontally disposed heater 11 is of the contact type and comprises a closed receptacle having an air vent connection 12 at one end and an inlet steam connection 13 at the other end. The vent connection communicates with a heater 14 of the surface type, shown as located above the contact heater 11 and to which all of the water to be heated is delivered prior to its delivery to the surface heater.

As illustrated, the heater 14 is of the surface or closed type and is provided with an air vent 15, which is shown as communicating with the atmosphere. Water to be heated is delivered to the heater 14 through a pipe 16, and after traversing the tubes 14^a of the heater 14, is delivered through a pipe 17 to the spray nozzles 18 of the heater 11. It will be apparent to those skilled in the art

that various types of heaters may be employed and that the details of construction of both the heaters may be materially modified without in any way departing from the spirit or scope of the invention as set forth by the appended claims. In the drawing I have illustrated a condensate return pipe 14^b communicating with the heater 14 and with the heater 11 below the normal water level of that heater. Other means may be employed for disposing of the water of condensation, but where an open communication such as illustrated is employed, the heater 14 should be raised above the heater 11 a sufficient height to prevent water from being forced from the heater 11 into the heater 14.

The working passage of the turbine 3 communicates with the receiver 10 through a system of piping 19. As illustrated, the piping 19 includes an ordinary form of pressure regulating valve commonly known as a constant pressure or heat balance valve which is diagrammatically illustrated at 21. The valve 21 is so arranged that it will open in response to the pressure of the fluid in the receiver 10 and deliver fluid therefrom to the turbine 3, when the pressure within the receiver exceeds a determined pressure. The pipe 19 also includes a manually operated valve 22 for permanently shutting off communication between the turbine and the receiver and the receiver may and preferably will be provided with a safety or pop-off valve 19^a such as is ordinarily employed for relieving excessive pressure. The valve 21 is also arranged to open in response to a decrease in pressure within the receiver 10 and to admit augmenting fluid or steam from the working passage of the turbine 3 to the receiver. For this reason, the piping 19 preferably communicates with the working passage of the turbine at such a point that the pressure normally existing at the point of connection is substantially equal to the pressure which it is desired to maintain within the receiver 10.

Assume for the purposes of description that 100,000 pounds of water are to be heated per hour from 100° F. to 216° F. and that the receiver 10 receives 20,000 pounds of exhaust steam per hour from the various sources communicating with it. Assume also that the constant pressure or heat balance valve 21 is so adjusted that it will not open in response to an excess of pressure in the receiver 10 until the pressure in the receiver is equal to or exceeds 16 pounds absolute. Under such conditions a pressure of 16 pounds absolute will be normally maintained in the heater 11, and steam will flow from the heater through the vent pipe 12 to the heater 14 in which atmospheric pressure (14.7 pounds absolute) is maintained due to the vent 15 being open to the atmosphere.

Assume also that the pipe 2 is of such size that under the conditions above set forth approximately 2000 pounds of steam per hour will flow from the heater 11 to the heater 14. The steam entering the heater 14 will be condensed therein by the 100,000 pounds of water passing therethrough and the temperature of the water will be raised from 100° to 119.35°, which as is apparent, 5 is not sufficient rise in temperature to cause the formation of scale in the heater 14 and consequently a surface heater such as illustrated may be employed. The water after passing through the heater 14, is delivered 10 to the heater 11, where it is mixed with the steam entering the heater from the receiver 10. As a result of the mixture of the steam and water approximately 10,000 pounds of steam are condensed and the water is 15 itself heated to 216° F. Inasmuch as only 2000+10,000 pounds, *i. e.* 12,000 pounds of the available steam can be employed in heating the feed water, the remaining 8000 will cause the constant pressure valve 21 to lift 20 and the excess steam will be delivered to the main power developing unit 3 and will do useful work therein in expanding to condenser pressure. It will be obvious that whenever there is more steam available than 25 can be condensed in the two heaters 11 and 14 that the pressure in the exhaust or receiver 10 and in the heater 11 will be at least equal to the pressure required to lift or open the constant pressure valve 21 and if there is 30 less steam than can be condensed in the two heaters, the vent openings 12 and 15 will prevent the pressure falling below atmosphere in the exhaust steam system. The constant pressure valve may be so adjusted that as 35 soon as the pressure in the exhaust main or receiver 10 falls below 15 pounds absolute, it will open and deliver steam from the main power unit to the receiver and thereby maintain approximately 16 pounds pressure in 40 the receiver.

From the above description it will be apparent that by properly proportioning the vent or passage 12 of the heater 11, with respect to the capacity of the heater 14, the 45 heater 11 will not only be properly vented, but all of the steam delivered to it will be efficiently employed in heating the feed water. As is apparent from the above description, the vent passage 12 and actuating mechanism of the valve 21 should be so proportioned that the valve 21 will open and relieve the pressure, within the receiver 10 or heater 11, when the pressure conditions are such that the vent passage 12 will pass more fluid 50 than the apparatus communicating with it is capable of effectively utilizing. While I have shown the heater 14 arranged to deliver the water passing through it to the heater 11, it will be apparent that this water 55 may be utilized elsewhere after it is heated

by the heater 14 and that the heater 14 may be replaced by any apparatus capable of utilizing low pressure fluid. It will also be apparent that various changes, modifications, substitutions, additions, and omissions 70 may be made in the apparatus illustrated without departing from the spirit and scope of the invention as set forth by the appended claims.

What I claim is:

1. A feed-water heating system comprising a closed contact heater, means for supplying heating fluid to said heater, a surface heater arranged above the contact heater, a vent connection between the contact and surface 80 heaters and having such capacity as to assure the transfer of the major portion of the heat in the contact heater, an atmospheric vent communicating with the surface heater, means for passing water successively through the surface and contact heaters, and a drain connection for conducting condensate from the surface heater to the contact heater.

2. A feed-water heating system comprising a closed contact heater, means for supplying steam to said heater, a surface heater arranged above the contact heater, a continuously open vent connection between the contact and surface heaters, a continuously 90 open atmospheric vent for the surface heater, means for passing water successively through the surface and contact heaters, and a connection for draining condensate from the surface heater to the contact heater.

3. A feed-water heating system comprising a closed contact heater, means for supplying steam to said heater, a surface heater arranged above the contact heater, a continuously open vent connection between the 105 contact and surface heaters, a continuously open atmospheric vent for the surface heater, and means for passing water successively through the surface and contact heaters.

4. A feed-water heating system comprising a horizontally disposed contact heater, means for supplying steam to one end thereof, a surface heater, a continuously open vent connection between the other end of 115 the contact heater and surface heater, a continuously open atmospheric vent for the surface heater, and means for passing water successively through the surface and contact heaters.

5. A feed-water heating system comprising a contact heater, means for supplying steam to one end thereof, a surface heater, a continuously open vent connection between the other end of the contact heater and the 125 surface heater for passing non-condensable gases and a portion of the steam to the surface heater where the heat thereof is transferred to the water passing through the surface heater, the vent connection having such 130

4
capacity as to assure the discharge of water from the heater at a temperature below the scale depositing temperature, a continuously open atmospheric vent for the surface heater, and means for passing water successively through the surface and contact heaters.

6. A feed-water heating system comprising a closed contact heater, means communicating with one end of the heater for supplying steam thereto, a surface heater arranged above the contact heater, a continuously open vent connection between the other end of the contact heater and the surface heater, and a continuously open atmospheric vent for the surface heater.

7. A feed-water heating system comprising a closed contact heater, means communicating with one end of the heater for supplying steam thereto, a surface heater arranged above the contact heater, a continuously open vent connection between the other end of the contact heater, an atmospheric vent for the surface heater, and a

drain connection between the surface and contact heaters.

8. A feed-water heating system comprising a closed contact heater, means communicating with one end of the heater for supplying steam thereto, a surface heater arranged above the contact heater, a continuously open vent connection between the other end of the contact heater and the surface heater for supplying non-condensable gases and a portion of the steam to the surface heater, the vent connecting having such capacity as to assure the major portion of condensation and heat transfer in the contact heater, a continuously open atmospheric vent for the surface heater, and a drain connection between the surface and contact heaters.

In testimony whereof, I have hereunto subscribed my name this 5th day of July, 1918.

WARREN B. FLANDERS.
